UNITED STATES PATENT OFFICE.

CHARLES WILLIAM WALSTROM, OF MINNEAPOLIS, MINNESOTA, ASSIGNOR TO MINNEAPOLIS BEDDING COMPANY, OF MINNEAPOLIS, MINNESOTA, A CORPORATION.

BED-FRAME.

1,243,234.

Specification of Letters Patent.

Patented Oct. 16, 1917.

Application filed March 13, 1916. Serial No. 83,803.

To all whom it may concern:

Be it known that I, CHARLES W. WALSTROM, a citizen of the United States, resident of Minneapolis, county of Hennepin, State of Minnesota, have invented certain new and useful Improvements in Bed-Frames, of which the following is a specification.

In the manufacture of bed frames where angle bars have been used for the ends of the frame, considerable difficulty has been experienced in preventing the vertical flange of the end rails from warping or buckling under the pull of the bed springs thereon.

The object of my invention is to provide a means for bracing the end rails and so distributing the strain thereon that bending or buckling of the flanges out of their normal plane will be avoided.

The invention consists generally in various constructions and combinations, all as hereinafter described and particularly pointed out in the claims.

25 In the accompanying drawings forming part of this specification,

Figure 1 is a plan view, partially in section, of a portion of the bed frame embodying my invention,

30 Fig. 2 is a transverse sectional view of the same,

Fig. 3 is a detail, sectional view, showing the manner of mounting the bridge in the end rail of the frame.

35 In the drawing, 2 represents the side rails of the frame, having castings 3 at the ends thereof to which the vertical flange 4 of the end rail is secured. The horizontal flange 5 of this rail has holes 6 therein for the connection of the coiled springs 7 of the spring fabric 8. To prevent buckling or bending of the end rail under the pull of the spring fabric thereon, I provide a truss bar 9 secured to the vertical flange of the

40 rail, preferably at 10. A bridge 11 is interposed between this truss and the flange 4 and is provided with a convex seat 12 to receive the truss bar. A lug 13 is provided on the bridge to engage the forward edge of

the flange 5 and the rear end of the bridge 14 is seated in the angle between the flanges 4 and 5, and the strain of the truss bar, instead of being transmitted through the bridge to the vertical flange 4, is directed into the angle between the flanges and this angle is sufficiently stiff to resist backward pressure without buckling or bending. I am thus able to apply the tension of the spring fabric to the end rail of the frame and utilize the truss bar for bracing the end rail without danger of bending or buckling the rail out of its normal position.

In various ways the details of construction herein shown and described may be modified and still be within the scope of my invention.

I claim as my invention:

1. In a bed frame, the combination, with an angle bar end rail having a horizontal and a vertical flange, of a truss bar, a bridge seated against the under surface of said horizontal flange and having means for engaging the forward edge thereof, the forward end of said bridge having a seat for said truss bar and the rear end of said bridge bearing on said rail in the angle between said vertical and horizontal flange.

2. In a bed frame, the combination, with an angle bar end rail having a horizontal and a vertical flange, of a truss bar secured at its ends to the vertical flange of said rail, a bridge seated against the under surface of said horizontal flange at a point mid-way substantially between the ends of said rail, and having a hook to engage the edge of said horizontal flange, said bridge having a recess wherein said truss bar is seated, the outer end of said bridge being seated in the angle formed at the junction of said horizontal and vertical flanges, and into which angle the pressure of the truss bar is transmitted by said bridge.

In witness whereof, I have hereunto set my hand this 29th day of February, 1916.

CHARLES WILLIAM WALSTROM.
